UNITED STATES PATENT OFFICE.

HARRY L. BEACH, OF COSHOCOTON, OHIO.

MATCH-SAFE.

No. 878,762.

Specification of Letters Patent.

Patented Feb. 11, 1908.

Application filed October 16, 1906. Serial No. 339,247.

To all whom it may concern:

Be it known that I, HARRY L. BEACH, a citizen of the United States, residing at Coshocton, in the county of Coshocton and 5 State of Ohio, have invented a new and useful Match-Safe, of which the following is a specification.

The invention relates to improvements in match safes.

10 The object of the present invention is to improve the construction of match safes, and to provide a simple and efficient one, designed for advertising and other purposes, and adapted to be cheaply constructed either 15 for holding a box of safety matches, or for holding parlor and other matches, which may be ignited by striking them anywhere.

With these and other objects in view, the invention consists in the construction and 20 novel combination of parts hereinafter fully described, illustrated in the accompanying drawing, and pointed out in the claims here-to appended; it being understood that various changes in the form, proportion, size 25 and minor details of construction, within the scope of the claims, may be resorted to without departing from the spirit or sacrificing any of the advantages of the invention.

In the drawing:—Figure 1 is a perspective 30 view of a match safe, constructed in accordance with this invention. Fig. 2 is a vertical transverse sectional view of the same, a box of safety matches being shown in position. Fig. 3 is a longitudinal sectional view, the 35 matches and match box being removed. Fig. 4 is an elevation of a match safe provided with a receptacle for loose matches. Fig. 5 is a detail view of a portion of the base, illustrating the construction of the raised pedestal en-gaging portion of the same. Fig. 6 is a plan 40 view, illustrating another form of the base, the pedestal supporting portions being of greater area than the bottom of the pedestal.

Like numerals of reference designate cor- 45 responding parts in all the figures of the drawing.

1 designates a base, which is in the form of a dish and which is provided with a central raised portion 2, adapted to fit within a 50 pedestal 3. The raised portion is oblong, and the pedestal 3, which is constructed of sheet metal, is tapered upwardly, being pro- 55 vided with inclined sides and having an open bottom. The pedestal consists of a single piece of sheet metal, which is cut diagonally

to form the sides and ends, and the latter are bent at an angle to the top 4 of the pedestal. The open bottom of the pedestal fits over and snugly embraces the raised portion of the base; and is provided with tongues 5, 60 which extend into slots 6 of the said raised portion 2. The slots 6 are formed in the sides and ends of the raised portion 2, and the tongues 5, which interlock the pedestal with the base, are arranged horizontally and 65 are located within the said raised portion at a point above the lower face of the base 1, so that the tongues 5 will not scratch or otherwise mar the finish of a table, or other surface on which the match safe may be placed. 70 The raised portion of the base forms a bottom recess, and by extending into the open bottom of the pedestal, it supports or braces the same against horizontal movement, and thereby relieves the tongues of strain.

75 The pedestal is provided at the top with parallel transverse slots 7, which receive tongues 8 of a safety match box holder or receptacle 9. The safety match box holder or receptacle 9 is composed of resilient clamp- 80 ing sides and a connecting bottom portion 10, from which the tongues 8 are cut. The tongues 8, which extend downwardly from the bottom of the match box holder or recep- 85 tacle 9, are bent against the lower faces of the top 4 of the pedestal, as clearly illus- trated in Fig. 3 of the drawing. The match box holder or receptacle is secured to the pedestal before the latter is applied to the base.

90 The clamping sides of the match box holder or receptacle are adapted to receive and en- gage a safety match box, and the side edges of the cover or outer portion of the match box are exposed between the sides of the 95 holder or receptacle for enabling the matches to be ignited on the box. Within the match box holder or receptacle is arranged an eject- 100 ing piece 11 of substantially rectangular form, consisting of horizontal top portion and vertical sides, which are provided at their lower edges with tongues 12. The top and sides are strengthened or reinforced by flanges 13 and 14, formed by bending the side edges of the said top and bottom portions 105 downwardly and inwardly, as clearly shown in Figs. 2 and 3 of the drawing. The tongues 12, which are located upon the top of the pedestal, extend downwardly through slots 15 of the bottom of the match box holder or 110

receptacle, and are bent against the lower face of the same. The ejecting piece, which is spaced from the sides of the match box holder or receptacle, is adapted to extend 5 into the outer portion or cover of a safety match box, and it forms a support for the inner portion or box in which the matches are arranged. The match box is placed end- wise within the holder or receptacle, and the 10 inner portion of the match box is caused to project above the outer portion or cover of the match box in the usual manner, as clearly illustrated in Fig. 2 of the drawing.

Instead of providing the match safe with a 15 match box receptacle or holder, as illustrated in Figs. 1 to 3 of the drawing, an ordinary rectangular receptacle 16, as illustrated in Fig. 4 of the drawing, may be used. The receptacle 16, which is designed to be provided with corrugated end walls to form 20 striking surfaces, is open at the top, and is provided at the bottom with integral tongues 17, which engage the top of a pedestal 18 in the same manner as the tongues 8 of the 25 match box holder or receptacle 9.

In Fig. 6 of the drawing is illustrated another form of base, which is provided with a raised portion 19 of greater area than the bottom of the pedestal. The pedestal 20 is 30 constructed similar to those heretofore described, and is secured to the raised portion 19 by tongues, which are received within the bottom recess formed by the said raised portion.

35 Either form of match safe, with either form of base, may be constructed sufficiently cheap to enable the same to be advantageously employed for advertising and other purposes.

40 Having thus fully described my invention,

what I claim as new and desire to secure by Letters Patent, is:—

1. A match safe comprising a base having a centrally raised rectangular portion forming a shallow recess on the bottom of the 45 base and provided in the side and end walls of the raised portion with slots, an upwardly tapered pedestal having an open rectangular bottom fitted over and snugly embracing the raised portion of the base and having inwardly extending tongues projecting through the slots into the bottom recess and held out of contact with the supporting surface on which the base may be placed, and a receptacle arranged on and secured to the pedestal. 50

2. A match receptacle comprising a base, a pedestal mounted on the base, a match box holder consisting of substantially vertical resilient clamping sides, and a connecting bottom fitted upon and projecting beyond the 60 pedestal and provided with tongues piercing the top portion of the pedestal and engaging the lower face of the said top portion, the bottom of the match box holder being also provided in its projecting portions with slots, and an ejecting piece arranged between and spaced from the sides of the match box holder and having a horizontal top and vertical sides provided at their lower edges with tongues 65 passing through the slots of the projecting portions of the bottom of the match box holder and engaging the lower face of the same. 70

In testimony, that I claim the foregoing as my own, I have hereto affixed my signature in the presence of two witnesses.

HARRY L. BEACH.
